UNITED STATES PATENT OFFICE.

FREDRICK E. WIGGINS, OF BRIDGEPORT, CONNECTICUT, AND GEORGE E. WIGGINS,
OF BOSTON, MASSACHUSETTS.

TRAVELING SEWING MACHINE AND METHOD OF SECURING MATERIAL TO CARRIER WIRES THEREFOR.

Application filed April 27, 1925. Serial No. 26,278.

This invention relates to a traveling sewing machine, and to a method of securing material to a wire adapted to carry said material. It has more particular reference 5 to a method whereby material ordinarily or preferably utilized to cover fields of shade-grown tobacco can be secured in novel and improved manner to a carrier- or supporting-wire for said material, and to a sewing 10 machine adapted to travel along said carrier- or supporting-wire to carry out the steps of the method.

At the present time shade-grown tobacco is covered by a suitable material supported 15 by lengths of wire several feet above the ground. Customarily, lengths of such wire are over thirty feet apart, there being across a field a net work of horizontal wires at right-angles or perpendicular to each other. 20 The material spans the spaces between the wires, and is secured to the carrier- or supporting-wires by hand. Usually, edge portions 25 of adjacent pieces or strips of material are wrapped about a wire, and the securing is manually accomplished by means of a needle and thread, the thread being passed through the material and about the wire. Such a method produces an unsatisfactory 30 connection between material and wire. Soon the elements acting upon the material cause stress upon the thread and a rubbing or chafing of thread and wire against each other with the result that there is during 35 a season considerable repairing to be done; an amount of repairing probably requiring more labor than that originally consumed in covering a tobacco field, which original labor is quite enough in itself.

An object of the present invention is to 40 provide a method whereby material can be secured to a wire by a continuous, uninterrupted operation, the method contemplating the advancement along a length of wire of a stitching entity in synchronism with a feeding entity, to accomplish the material securing result desired.

A further object is to provide a method 45 of securing material, such as that to cover a tobacco field, to a carrier- or supporting- 50 wire therefor in such manner that strains upon the material, principally due to the elements, can cause no rubbing or chafing of thread and wire against each other, the method contemplating the production of se-

curing stitches in the material in spaced relation to the carrier- or supporting-wire and so arranged that strains upon the material will have a tendency to move said stitches away from the wire, rather than toward it. 55

And a further object is to provide a novel 60 and improved sewing machine adapted to travel along a wire to carry out the steps of the method.

With the above objects in view, as well as others which will appear as the specification 65 proceeds, the invention will now be fully described and will hereinafter be specifically claimed, it being understood that the disclosure herein, as it relates to both the machine and the method, is merely illustrative 70 of principle and meant in no way in a limiting sense, changes in details of construction and arrangement of parts of the machine, and in the succession of operations of the method, being permissible so long as within 75 the scope of the appended claims.

In the accompanying drawings forming a part of this specification,

Fig. 1 is a side elevational view of a machine capable of carrying out the steps of the 80 method and in which the features of the invention are incorporated, disclosing a carrier- or supporting-wire in section, and adjacent portions of shade-material as when being stitched together and about the wire; 85

Figs. 1^a and 1^b are, respectively, an enlarged cross-sectional view through a carrier- or supporting-wire disclosing adjacent 90 portions of material secured thereto, and a diagrammatic view of the double lock stitch made by the machine disclosed;

Fig. 2 is a front elevational view of the machine, as seen from the right in Fig. 1;

Fig. 3 is a sectional view on line 3—3 in Fig. 1; 95

Fig. 4 is a sectional view on line 4—4 in Fig. 1;

Fig. 5 is a partial elevational view as seen from the top in Fig. 1, detailing portions of the mechanism; 100

Fig. 6 is a fragmentary sectional view on line 6—6 in Fig. 3; and

Fig. 7 is a sectional view on line 7—7 in Fig. 2.

A description of the construction and mode of operation of the improved traveling sewing machine will make plain the several steps of the method of the invention. 105

Broadly, the method contemplates the advancement along a length of wire of stitching entity in synchronism with a feeding entity for said stitching entity to accomplish 5 in continuous, uninterrupted manner the securing of material, such as that used to cover a tobacco field, to said length of wire. And the sewing machine, broadly, includes stitching mechanism in combination with 10 mechanism for feeding the machine along a wire, said stitching mechanism and machine feeding mechanism being synchronous.

With respect to the drawings, 10 represents the machine frame, which is of general 15 C shape, and 11 indicates a standard integral with or secured to the frame 10 in any suitable manner.

As disclosed, the standard 11 is made of 20 three metal strips. See Figs. 2 and 3. 12 and 13, respectively, are twine cases, the former containing a spool of twine or thread 14 for the needle, and the latter containing a similar spool for the looper, of the machine. Bands or hoops 16 of metal, enveloping 25 the twine cases and secured to the three metal strips of the standard in any convenient way, fix the relation of the twine cases to the frame. The structure described is for the sake of lightness. The twine or 30 thread can be associated with the machine frame in some other ordinary or preferred manner. Desirably, each spool 14 rests upon a removable base 17 in each twine case 12, 13. As shown, the bases 17 are 35 secured in the twine cases by means of bayonet locks 18. Each base has a handle 19 upon its outer or lower face for better manipulating the base when locking or releasing it, and has upon its inner or upper face a post 20 adapted to enter a spool 14 to stabilize said spool. The spools disclosed 40 are of frustro-conical shape, although they need not be so shaped.

Numeral 21 denotes a main shaft mounted 45 in bearings 22 of the frame 10, and 23 represents a stud fixedly mounted in said frame at right-angles to and near one end of said main shaft. A balance or fly wheel 24 upon the stud is for the purpose of rotating the 50 main shaft, and, as shown, said wheel has an actuating handle 24' whereby said main shaft can be manually rotated. Clearly, the main shaft could be power driven. The balance or fly wheel has a long hub 25 the 55 inner end of which is provided with a bevel gear 26 meshing with a smaller bevel gear 27 on the main shaft whereby each revolution of the balance or fly wheel rotates the main shaft an amount preferably greater 60 than a single revolution (two revolutions as shown).

The stitching mechanism and the machine feeding mechanism are both actuated from the main shaft 21, and for each revolution 65 of the main shaft there is, preferably, one

stitch made and a feed ahead of the machine one step, said one stitch and one step of feed being synchronous; that is, being equal to each other in timing and spacing. Evidently, a single rotation of the main shaft 70 could produce more than one stitch and one step of feed so long as the stitching and feeding are synchronous.

The bevel gear 27 on the main shaft 21 has secured to it a crank plate 28 with crank pin 29 preferably of ball type construction. 30 is a connecting rod with socket at one end engaging the ball crank pin 29 and with socket at opposite end engaging a ball crank pin 31 of a 80 needle bar lever 32. The needle bar lever is pivoted upon a stud 33 secured to the frame 10, and is pivoted at 34 to a needle bar 35 mounted in bosses 36 of the frame 10 to be longitudinally movable. Clearly, rotation of the crank plate 28 causes the needle bar to reciprocate. 37 is a thread eye and 38 is a needle of the needle bar. The needle may be held to the needle bar in regular 85 fashion by a chuck.

Numeral 39 represents a crank plate upon the end of the main shaft 21 opposite the crank plate 28, and 40 is a crank pin on said plate which engages in a cam slot 41 of a looper reciprocating lever 42 pivoted at 43 90 in the base 44 of the frame in convenient manner. This base 44 has two bearings 45 for a looper rockshaft 46. The looper rockshaft is longitudinally movable in the bearings 45, as well as oscillatable therein, and reciprocatory movement is imparted to said rockshaft by said looper reciprocating lever 42. To this end, the rockshaft has a collar 47 with pin 48 entering an elongated slot 49 in said looper reciprocating lever 42. 105

Intermediate the ends of the main shaft 21 is a mitre gear 50 which meshes with a mitre gear 51 fixed upon a short perpendicular shaft 52 rotatably mounted in a protuberance 53 of the frame. The end of this 110 short shaft spaced from the protuberance has a crank plate 54 with ball crank pin 55 engaged by a socket at one end of a connecting rod 57. The other end of said connecting rod 57 has a socket engaging a ball 115 crank pin 58 upon a looper lever 59 fixed upon the looper rockshaft 46. 60 is a looper upon said looper lever, and 61 are thread eyes of said looper.

Clearly, the connection between the mitre 120 gear 50 upon the main shaft 21 and the looper lever 59 as described, causes the looper to be rocked in the direction of its length when the main shaft is rotated, while the connection between the crank plate 39 and the looper rockshaft causes said looper to reciprocate transversely. It is sufficient to say for the purposes of the present invention, that the movements of the needle and looper, all operated from the main shaft 21, synchro- 130

nize to that extent necessary to produce the old and common form of double lock stitch more particularly disclosed in Fig. 1^b, and we consider it unnecessary to follow through the specific manner of making the stitch, principally for the reason that we do not intend to be limited to any particular type of stitch, although it now seems preferable to utilize a type of stitch which can be made by a looper, or its equivalent, rather than by devices which carry whole spools of thread at the direct location of the making of the stitches.

The main shaft 21 also carries an eccentric 15 62 with eccentric strap 63 which is pivoted at 64 to a block 65 adjustable in a longitudinal slot 66 of a pawl carrier 67. This pawl carrier is freely mounted upon a feed roll shaft 68 adjacent a ratchet 69 fixed upon said feed shaft 68. 20 70 are pawls on the pawl carrier, and 71 are springs urging the pawls into the teeth of the ratchet. 72 is a pawl stop on a block 72' fixed on the bed plate 73 secured to the frame and having 25 an opening allowing traverse of the needle. 72" is a spring urging the pawl stop into the ratchet. The feed roll shaft 68 has bearings 75 adjacent each of its ends, the bearings being in bosses 76 upon the frame 30 10. Said shaft 68 also has a feed roll 77 at one of its ends, and a gear 78 at its opposite end, said gear 78 meshing with a similar gear 79 upon a feed roll shaft 80 which has a feed roll 81 arranged adjacent and preferably in alignment with the feed roll 77. 35 Each feed roll 77, 81 desirably includes a grooved portion 82 to engage about a wire and material upon said wire, and a knurled portion 83 adjacent said grooved portion, 40 the grooved portions being adapted to lie against a wire and material thereon directly opposite each other, and the knurled portions being adapted to also lie directly opposite each other in firm engagement with 45 material (preferably at the seam) secured to said wire. The whole arrangement is adapted to be such that as the feed rolls rotate, they grip the wire and material and feed ahead, carrying the remainder of the 50 sewing machine along. Clearly, the connection between the eccentric 62 on the main shaft 21 and said feed rolls as fully described, causes the feed rolls to be actuated upon rotation of the main shaft. The adjustable connection between the eccentric 55 strap 63 and the pawl carrier allows for adjustment of the machine feed mechanism in order that there can be synchronism between the stitching mechanism and said feed 60 mechanism, as will be understood. The pawls 70 insure that the pawl carrier is locked to the ratchet as soon as actuation of said pawl carrier in the feeding direction of the feed rolls is attempted. Upon the 65 reverse movement of the pawl carrier, the

pawls ride over the ratchet teeth. The pawl stop, obviously, engages the teeth of the ratchet to preclude reverse movement of the ratchet, as well as of the feed rolls, while the pawl carrier and pawls are moving in the non-feeding direction of the feed rolls.

The upper portion of the shaft 80 is mounted in a boss 84 on the frame 10 and similar to a boss 76. Intermediate its ends this shaft 80 has a universal joint 85, and 75 the end portion of said shaft adjacent the feed roll 81 is mounted in a bearing 86 pivoted to a feed tension rod 87 slidably mounted in bosses 88 and 89 of the frame 10. A coil spring 90 upon the rod 87 engages at one end against a collar 91 fixed upon said rod 87, and at its other end against the boss 88 to cause the feed roll 81 to resiliently press against the feed roll 77. The universal joint 85 is constructed to insure that 85 the feed roll 81 will rotate upon rotation of the gear 79.

Numeral 92 represents a presser foot (which may be a folding guide) fixed at 93 to a presser foot tension rod 94 also mounted 90 in the bosses 88 and 89. A coil spring 90' upon the rod 94 engages at one end against a collar 91' fixed upon said rod 94, and at its other end against the boss 88 to cause the presser foot to resiliently engage the bed 95 plate 73. 95 is an opening in the presser foot allowing traverse of the needle. The presser foot can be of any suitable construction. We have preferred to show it as extending partially about the wire upon 100 which the sewing machine travels.

Numeral 96 denotes a collar fixed upon the upper end of the rod 87, and 97 is an arm extension of said rod 87 slidably arranged upon the rod 94 and normally situated in spaced relation to a collar 98 fixed upon the end of said rod 94 opposite the presser foot. 99 is a lever of a feed roll and presser foot lifter which is pivoted upon a part of the frame as at 100 and has engagement with said collar 96. Actuation of the lever 99 causes the feed rolls to disengage, and also causes the presser foot to be lifted from the bed plate. The clearance between the arm extension 97 and the collar 98 allows 115 the feed roll 81 to be removed from the feed roll 77 before the presser foot is lifted from the bed plate. This feature makes provision for releasing the feed rolls independently of the presser foot. 120

Numeral 101 represents grooved carrier wheels rotatably mounted upon the bed plate to support the machine upon a length of wire, and 102 represents a grip upon the machine frame, or upon the standard, whereby the machine can be better controlled as it rides along said length of wire.

The twine cases preferably include tubes 103 through which the thread passes to the needle and the looper, respectively. As dis-

closed, the thread for the looper is passed through a double eye 105 on the frame, thence over a rod 106 and between elements of a tension device 107 upon said rod, thence 5 again through said double eye 105, thence about the looper rockshaft, and thence through the spaced eyes in the looper. The thread for the needle is passed through a double eye 108 on the frame, thence over a 10 rod 109 and between elements of a tension device 110 upon said rod 109, thence again through said double eye 108, thence through the eye of a needle bar, and thence through the eye of the needle.

15 The manner in which the sewing machine operates is obvious. Adjacent portions of pieces or strips, denoted A and B, respectively, of material to be secured upon the wire C are folded together in any suitable 20 manner and about said wire C. The grooved carrier wheels 101 are caused to rest upon said wire (preferably upon material wrapped about the wire) to support the machine while operating, and the feed rolls, 25 presser foot and bed plate are made to engage said wire and material in the manner already fully set forth. Upon rotation of the balance or fly wheel the main shaft is rotated to actuate the stitching mechanism 30 and forward feeding mechanism so that the timing and spacing of the stitching operation are equal to the timing and spacing of the feeding operation; that is, so that the stitching and feeding operations synchronize. 35 Desirably, the feed rolls are behind the needle and looper (considering the direction of feed), so that the feed of the machine upon the wire and material is obtained by action of feed rolls which are working 40 upon secured material; that is to say, the feed rolls advance along the line of the seam as it is made by the needle and looper of the machine.

45 It is to be noted that the seam is made in spaced relation to the wire C (below said wire as disclosed, the needle of the sewing

machine being beneath the plane of the wire). This accomplishes an important result. Strains upon the material can cause no rubbing or chafing of thread and wire against each other because there is no possibility of thread and wire contacting, it being evident that drawing, stretching, or straining of the material has a tendency to move the seam or stitching away from the wire. All strains are thus resisted by the portions of material wrapped about the wire.

What we claim is:

1. In a sewing machine adapted to attach sheet material looped over a suspended wire to the wire, means for supporting a sewing machine on said wire for movement therewith, means having a groove therein substantially concentric with the wire for pressing the looped material into contact with the wire, means for pressing the portions of the material depending at opposite sides of the wire into contact with each other closely adjacent the wire, and means for forming stitches through the contacting portions of the sheet material.

2. In a sewing machine adapted to be supported upon a suspended wire for movement therewith and to attach sheet material looped over said wire to the wire, means having a groove therein substantially concentric with the wire for pressing the looped material into contact with the wire, means for pressing the portions of the material at opposite sides of the wire into contact with each other adjacent the wire, and means for forming stitches through the contacting portions of the sheet material.
